Specification for Design.

Patented Nov. 14, 1916.

Application filed August 12, 1916. Serial No. 114,648. Term of patent 14 years.

To all whom it may concern:

Be it known that we, EUGENE AULICINO, a subject of the King of Italy, and JAMES P. FRAGETTA, a citizen of the United States, residing at Utica, in the county of Oneida and State of New York, have invented a new, original, and ornamental Design for a Table-Receptacle for Holding a Salt-Cellar, Pepper-Shaker, Knives, Forks, Spoons, and Toothpicks, of which the following is a specification, reference being had to the accompanying drawing, forming part thereof.

The figure is a perspective view of a table

receptacle for holding a salt cellar, pepper shaker, knives, forks, spoons, and toothpicks, showing our new design.

We claim:

The ornamental design for a table receptacle for holding a salt-cellar, pepper shaker, knives, forks, spoons and toothpicks, as shown.

EUGENE AULICINO.
